ABRASIVE SUPPORTING MEMBER AND
METHOD OF PRODUCING SAMEKenneth H. Bowen, Auburn, N. Y., assignor to
Columbian Rope Company, Auburn, N. Y., a
corporation of New York

Application June 10, 1935, Serial No. 25,895

5 Claims. (Cl. 51—197)

This invention relates to improvements in abrasive supporting members and method of making same.

In certain machines on the market at the present time, commonly referred to as sanding machines, the abrasive material is supported on a revolving member, the arrangement being such that the abrasive surface can be renewed, thus permitting the supporting member proper being reused any number of times. In some types of machine, the abrasive material is applied to the periphery of a supporting member adapted to be rotated at the desired speed, while in other instances, the abrasive, in sheet form, is removably secured against the side face of a revolvable, disk-like body, capable of flexing under lateral stresses. In the latter type of supporting member, means are also usually provided for preventing excessive or destructive flexing of the supporting member, but in all types, the supporting member proper is secured on a core which is adapted to be mounted on a shaft for imparting rotary motion to said member.

One object of the present invention is to provide a supporting member in which the core is provided with means for transmitting the rotary motion of the core to said supporting member proper.

Another object is to provide a disk-like support capable of flexing laterally, but in which means are provided on the core for resisting such flexing action.

A further object is to provide a device of this character wherein the supporting surface for the abrasive is formed by a body composed of a length of fibrous elements arranged in superposed convolutions around the periphery of a core, with means projecting radially from the core into said fibrous body whereby driving strains will be transmitted from the core to said body and, in constructions where the abrasive is supported on the side of the fibrous body, lateral flexing of said body will be resisted.

A still further object is to provide an abrasive supporting member which can be produced at low cost and which will consist of a minimum number of parts as by providing the driving means on the core and simply winding a length of fibrous elements on said core whereby a body of superposed, radially arranged convolutions will be formed on said core with said driving means engaging the inner radial portion of the fibrous body.

With these and other objects in view, the invention consists in certain details of construction and combinations and arrangements of parts, all

as will hereinafter be more fully described and the novel features thereof particularly pointed out in the appended claims.

In the accompanying drawings—

Figure 1 is a side elevation of a supporting member, usually termed a "pad", produced in accordance with the present invention;

Fig. 2 is a transverse sectional view of the structure illustrated in Fig. 1;

Fig. 3 is a similar view, illustrating a modified construction of the driving elements;

Fig. 4 is an elevational view of the core and driving elements of the structure shown in Figs. 1 and 2;

Fig. 5 is an edge view of the core shown in Fig. 4;

Fig. 6 is a sectional view of the structure shown in Fig. 3, this view being taken at right angles to said Fig. 3;

Fig. 7 is an edge view of a still further modification of the core and driving elements, the "pad" being indicated in dotted lines;

Fig. 8 is a modified form of driving elements;

Fig. 9 is a transverse section showing a modified pad construction with the core and driving elements used in the construction shown in Figs. 1 and 2;

Fig. 10 is a transverse sectional view illustrating a "pad" mounted on a driving shaft;

Fig. 11 is an edge view of a still further modification of the core and driving elements; and

Fig. 12 is a transverse section illustrating another form of core and driving elements incorporated in an abrading roll or wheel, as distinguished from a "pad" construction.

The "pad" or fibrous body portion of the support may be of varying construction, but is preferably formed up by winding a length of fibrous elements, coated with a suitable binder, in successive convolutions on a core 10. Preferably, the fibrous elements are individual fibers. Such a fibrous body is indicated at 11. The formation of fiber supporting pads or bodies of this type is more fully described and claimed in applications, Serial Nos. 8,762 and 8,763, filed February 28, 1935.

As before mentioned, the core or center 10 is adapted to be mounted for rotary motion. The entire assembly of one form of pad or support is illustrated in Fig. 10. Here, the shaft 12 is provided with a collar 13 and a threaded extremity beyond said collar to receive a plate 14 which abuts against said collar. Core 10, with the disk-like abrasive supporting body 11, is secured

to the plate by bolts 15 and a sheet of abrasive material 16 is held in position against one side face of the supporting body by a flanged sleeve 17 threaded on the shaft. With a supporting body of the type illustrated in this figure, one or more backing plates 18 are provided at the opposite side of the body to prevent undue flexing of said body by strains imposed laterally thereon when the working face of the device is pressed against the surface being operated upon.

With such an assembly, it is desired that the driving force of the shaft be transmitted from core 10 to the disk-like body 11 and in the present instance this is accomplished by driving

means provided on the core itself and engaging the inner radial portion of body 11. For instance, in the construction of Figs. 1 and 2, the core is formed with a plurality of pins 19 projecting radially from its periphery into the mass of fibers.

It might be mentioned at this point that the fibers, in being wound on the core, are preferably brought together with a tongue and groove arrangement, as shown in Fig. 2, as such a construction aids in preventing damage to body 11

by shearing action set up by lateral strains imposed thereon under working conditions. However, the interlock thus formed is not essential and may be omitted, as shown in Fig. 3.

The pins 19 may, or may not, be formed integrally with the core. As illustrated in Fig. 3, they may be formed on a metal band 20, secured on the periphery of the core. The pins 19 may also be made of any desired length. As shown in Fig. 8, they may be short and struck up out of the band 20 itself. On the other hand, comparatively long pins may be used as in Figs. 3 and 6. The longer pins are advantageous in that they reinforce fiber body 11 against the lateral stresses previously mentioned. In fact, by making the pins of sufficient length and heavy enough, they can be used in lieu of the backing plate 18 in the complete assembly. Also, the pins may be offset laterally from one another as shown in Fig. 7.

Where the tool is to be operated at comparatively low speeds so that the driving forces are not too great, the core 10 may be simply provided with a serrated or knurled surface 21, as shown in Fig. 11.

Fig. 12 shows a core member for an abrading roll whose peripheral surface is used as the working surface, usually having an abrasive substance applied thereto, although it may be used in buffing or polishing operations. Here, the pins 19, more

or less in the form of radially projecting studs, are cast integrally with the core.

With any of the forms illustrated, the production and use of the core 10 and pad or roll body 11 is greatly simplified. As to production, it is only necessary to provide the desired form of driving means or elements on the core and wind the fibers thereon. As to use, especially where the longer projections are used for lateral reinforcement of the pad, the tool can be more quickly assembled, as the backing plates 18 can be omitted. Also, as previously stated, each form provides a positive drive between the core and body 11.

What I claim is:

1. An abrasive supporting member comprising a core adapted to be mounted for rotary movement, a fibrous disk-like body extending radially from said core, said body being capable of flexing laterally, and laterally flexible driving means on said core for transmitting rotary motion from said core to said body, said driving means extending radially into said body and yieldingly resisting lateral strains on said body.

2. An abrasive supporting member comprising a core adapted to be mounted for rotary motion, a fibrous laterally flexible disk-like body extending radially from said core, and a plurality of laterally flexible pins extending radially from said core into said fibrous body.

3. An abrasive supporting member comprising a core adapted to be mounted for rotary motion, a laterally flexible fibrous disk-like body projecting radially from the periphery of said core, a band extending around said core, and a plurality of laterally flexible, radial projections on said band extending into said fibrous body.

4. An abrasive supporting member comprising a core adapted to be mounted for rotary motion, a flexible disk-like fibrous body extending radially from the periphery of said core, and a plurality of laterally flexible projections secured to said core and extending radially into said fibrous body, a portion of said projections being offset laterally from the others.

5. An abrasive supporting member comprising a core adapted to be mounted for rotary motion, a flexible disk-like fibrous body extending radially from the periphery of said core, a band secured on said core, and a plurality of laterally flexible projections formed on said band and projecting radially into said fibrous body, a portion of said projections being offset laterally from the others.

KENNETH H. BOWEN.
